UNITED STATES PATENT OFFICE.

CHARLES M. WALL, OF CURWENSVILLE, PENNSYLVANIA, ASSIGNOR OF ONE-HALF TO
JAMES A. BICKFORD, OF CURWENSVILLE, PENNSYLVANIA.

PRESS-BOX.

1,108,643.

Specification of Letters Patent. Patented Aug. 25, 1914.

Application filed April 12, 1913. Serial No. 760,781.

To all whom it may concern:

Be it known that I, CHARLES M. WALL, citizen of the United States, residing at Curwenville, in the county of Clearfield and 5 State of Pennsylvania, have invented new and useful Improvements in Press-Boxes, of which the following is a specification.

My present invention pertains to press boxes such as are used in the manufacture of 10 brick, etc.

The object of my invention is to provide a press box of such construction that a single exterior casting may be used for the 15 pressing of bricks, etc. of various sizes and shapes within certain limits. Thus a certain size of exterior casting may be used for a series of different sizes of bricks, a larger exterior casting may be used for a series of 20 larger different-size bricks, and a smaller exterior casting may be used for a series of smaller different size bricks. In this way 25 a few exterior castings may be made to serve the purpose of a larger number of exterior castings as used in the manner now in vogue, and this will be appreciated as 30 an important advantage when it is stated that the said exterior castings are the most expensive part of a press box.

With the foregoing in mind the invention 35 will be fully understood from the following description and claims, when the same are read in connection with the drawings, accompanying and forming part of this specification, in which:

Figure 1 is a vertical transverse section 40 of a press box embodying my invention. Fig. 2 is a plan of the same. Fig. 3 is a detail elevation of one end portion of one of the side liners comprised in the box and 45 showing the notch in the end of the said side liner registered with the groove in the end of the adjacent end liner, as one method of holding same in place. Fig. 4 is a detail view, partly in plan and partly in horizontal section, the sectional part being taken in 50 the plane indicated by the line 4-4 of Fig. 3. Fig. 5 is a fragmentary section of the box illustrating a modification hereinafter specifically referred to.

Referring by numeral to the said drawings, and more particularly to Figs. 1 to 4 thereof: 1 is the exterior member or casting of the box, and 2 is a lining arranged in 55 and permanently connected to the exterior casting. The said lining 2 is preferably of

steel, though it may be of any other material consonant with the purpose of my invention, without involving departure from the scope of the invention as claimed. Inferiorly the said lining 2 is slightly tapered 60 downwardly and inwardly, as clearly appears in Fig. 1.

Arranged within the lining 2 and spaced therefrom and extending, by preference, above the casting 1 and the said lining 2, are 65 side liners 3 and end liners 4. These liners 3 and 4 are simply smooth plates, preferably of steel, which are of even thickness throughout and are the same on both sides and have ends which are identical in construction with each other. From this it follows that both 70 sides of the liners are adapted to be presented to the bricks to be pressed, and that each liner is susceptible of being reversed and used upside down. This is materially 75 advantageous inasmuch as it prolongs the usefulness of the liners 3 and 4 to an indefinite extent. It will also be noted that the liners being smooth and of even thickness throughout, can be inexpensively produced. 80

Formed in the ends of one pair of liners, preferably the side liners 3, and midway between the upper and lower edges of said liners, are notches 5, Figs. 3 and 4, and 85 formed in the edges of the other pair of liners, preferably the liners 4, and at points midway between the lower and upper edges thereof, are grooves 6 which are opposed to and arranged in communication with the 90 notches 5. The said notches 5 and the grooves 6 are employed in order to enable the Babbitt metal or other poured or plastic filler employed to occupy the said notches and grooves, and in that way key one pair of 95 liners to the other pair of liners. In this connection it will be understood that the plastic filler will serve the purpose stated by occupying the notches and entering the grooves opposed to the open sides of the 100 notches.

The filler I employ is indicated by 7, and is preferably formed by Babbitt metal or other poured metal or alloy of metals, though it might be formed of plastic material suitable to the purpose. The said filler fully occupies the spaces between the lining 2 and the liners 3 and 4, and supports and backs and retains solidly in position the 105 said liners 3 and 4. As will be observed by 110

reference to Fig. 1, the filler 7 of poured metal or alloy of metals is retained in position by the downward taper of the interior of the lining 2.

- 5 As shown by full lines in Fig. 2, the liners 3 and 4 are arranged to receive a rectangular or oblong brick. In this connection it will be noticed that by using different sizes of liners 3 and 4, and placing a filler 7 so 10 as to fully occupy the spaces between the said liners and the lining 2, bricks of different sizes may be pressed in the same exterior casting 1. I would also have it understood that bricks of different shapes and 15 different sizes may be also pressed in the same exterior casting 1; it being simply necessary to employ and place liners 3 and 4 appropriate to the shape and size of the brick to be pressed in the lined casting 1, 20 and then place a filler 7 so as to fully occupy the spaces between the said liners 3 and 4 and the lining 2 of the casting 1. For instance in Fig. 2, the side liners 3 are indicated by dotted lines as inclined inwardly 25 toward one end of the box for the pressing of a key brick. When the side liners 3 are so arranged a shorter end liner 4 is employed at one end of the inclosure formed by the liners, and a filler 7 is placed to fully 30 occupy the spaces between all of the liners and the lining 2 of the exterior casting 1. When it is desired to press in the box a curved brick, curvilinear side liners are substituted for the straight side liners 3, and 35 appropriate end liners are employed between the ends of the said curvilinear side liners in the same manner that the end liners 4 are arranged between the side liners 3, as shown in Fig. 2.
- 40 In all cases when the filler 7 is placed about the side, and end liners, and between the said liners, and the lining 2 of the casting 1, it will be observed that by occupying the notches 5 and the complementary grooves 45 6, the filler will serve to key and hold the side liners and end liners together in proper relation, and in such manner that there is no liability of any liner being casually displaced incidental to the repeated use of the 50 press box.
- In Fig. 5, I have shown the lining 2^a of the exterior casting or member 1 as formed of a poured plastic material, cement, for instance.
- 55 While I prefer to provide the exterior casting or member 1 with a lining such as 2 or 2^a, I do not desire to be understood as

confining myself to lining the said exterior casting or member 1.

When no lining, such as 2 or 2^a is provided in the casting or member 1, the said casting or member will, by preference, be so shaped that its interior will be tapered downwardly and inwardly. 60

Having described my invention, what I claim and desire to secure by Letters-Patent, is:—

1. A press box comprising an exterior member, pairs of liners disposed in the exterior member and spaced from the interior thereof; one pair of said liners having notches in their ends and the other pair of liners having grooves in their ends registered with the notches of the first-named pair, and a filler occupying the spaces between the interior of the exterior member and the outer sides of the liners and also occupying the notches and the complementary grooves of the liners, and securing said liners together and in position. 70

2. A press box, comprising an exterior member, pairs of liners disposed in the exterior member and spaced from the interior thereof; all of the said liners being smooth at their opposite side and of even thickness 80 throughout, and one pair of liners having notches in their ends midway between their upper and lower edges and the other pair of liners having grooves in their ends midway between their upper and lower edges and 85 registered with the notches of the first-named pair, and a filler occupying the spaces between the interior of the exterior member and the outer sides of the liners and also occupying the notches and the complementary grooves of the liners, and securing said liners together and in position. 90

3. A press box, comprising an exterior member, a lining permanently arranged in the exterior member and having an interior 100 that is tapered downwardly and inwardly, liners disposed in the exterior member and spaced from the said lining thereof, and a poured filler occupying the spaces between the said lining and the outer sides of the 105 liners, and securing said liners together and in position.

In testimony whereof I have hereunto set my hand in presence of two subscribing witnesses.

CHARLES M. WALL.
